UNITED STATES PATENT OFFICE.

JUSTIN F. BARBOUR, OF CHICAGO, ILLINOIS.

FILING-RACK FOR LOOSE-LEAF BINDERS.

1,286,912.

Specification of Letters Patent.

Patented Dec. 10, 1918.

Application filed September 6, 1917. Serial No. 189,977.

To all whom it may concern:

Be it known that I, JUSTIN F. BARBOUR, a citizen of the United States, residing at Chicago, in the county of Cook and State of Illinois, have invented a certain new and useful Improvement in Filing-Racks for Loose-Leaf Binders, of which the following is a specification.

My invention relates to improvements in filing racks for loose leaf binders and the like and it is adapted to furnish an arrangement whereby means may be provided for holding and supporting a loose leaf binder with covers separated so that the pages or cards therein contained may be freely and easily moved back and forth and separated for the insertion and withdrawal of the ordinary type of cut removable sheets. My apparatus is arranged so that the binder itself will be firmly and rigidly held in position and so that means will be provided for continuing the ordinary posts of the binder in such wise that the sheets themselves will not be cut or caught between the component parts of the posts. This arrangement makes it possible to use a binder in which the posts do not project beyond the cover and at the same time insure that the binder and its contents will be always maintained in the proper relation when being filled. Other objects will appear from time to time in the specification.

My invention is illustrated more or less diagrammatically in the accompanying drawing, wherein—

Figure 1 is a side elevation;

Fig. 2 is a section on the line 2—2 of Fig. 1;

Fig. 3 is a plan view of one of the removable sheets;

Fig. 4 is a plan view of a preferred form;

Fig. 5 is a side elevation of Fig. 4;

Fig. 6 is a section on the line 6—6 of Fig. 4;

Fig. 7 is a section on the line 7—7 of Fig. 4;

Fig. 8 is a plan with parts in section of a modified form;

Fig. 9 is a side elevation of such modified form;

Fig. 10 is a section on the line 10—10 of Fig. 8;

Fig. 11 is a section on the line 11—11 of Fig. 8.

Like parts are indicated by like characters in all the figures.

A is a supporting base. Upon it is mounted an end stop A¹ held rigidly in position by means of screws A². A³ is a cover support inclined up and outwardly from the end stop A¹. A⁴ is a similar stop carrying a cover support A⁵ opposed to the cover support A³. A⁶ is a rod slidable through the stop A⁴ adapted to be held against longitudinal movement by means of the set screw A⁷ and normally engaging the perforated end B⁵ of the binding post. There may be a plurality of such rods and each one will be separately mounted for adjustable movement.

B is a loose leaf book. It has two opposed clamping members B¹, B² upon which are pivoted book covers B³. B⁴ is a sectional binding post, one of the sections comprising such binding post being rigidly mounted in the member B¹, the other sections being screw-threaded or fastened one to another so as to make up the desired length. The last section B⁵ passes through the clamping member B² and is adapted to be held against movement in an outward direction by the clamping lever B⁶ held in the clamping position by a spring B⁷ and adapted to be released by a sliding bar B⁸ moved by the operator toward the clamping ring and rotating it when it is desired to release the clamping member B². B⁹ are removable loose leaves held between the members B¹, B² provided with perforations B¹⁰ to engage the binding posts B⁴. Slots B¹¹ communicate with these perforations and make it possible to place the separate leaves in position without withdrawing the binding post.

B¹² are raised steps designed to support the member B¹ slightly above the base A so that when the member B² and the leaves B⁹ are moved along the rods B⁴ or A⁶ they will not drag upon the base.

In a different form of my invention C is a platform upon which are rigidly mounted stop members C¹ connected by the bar C² to engage the binding portion of the loose leaf book and having inclined cover supports C³ which will permit the cover to swing to one side but limit it in its movement. This platform C is slotted at C⁴. It has on its upper surface a guide rail C⁵ through which the slot C⁴ opens. C⁶ is a shoe adapted to

travel upon the guide rails C^5 and to be held by its form against rotational movement while free to move longitudinally. C^7 is a bracket or cross beam mounted upon the shoe C^6 . C^8 is a locking pin passing through the shoe and cross beam terminating in the head C^9 adapted to travel in a slot C^{10} on the under side of the platform C . This member C^8 is located within the slot C^4 and projects up above the bracket C^7 and has pivotally mounted upon it an eccentric cam C^{11} adapted to be controlled by the handle C^{12} to engage the plate C^{13} whereby when in the position shown in Fig. 7 tension will be exerted by the eccentric to clamp the shoe and bracket or carriage C^7 in position on the platform and hold them against longitudinal movement. The parts are thus free to move toward and from one another to engage loose leaf books of varying sizes.

The bracket C^7 is slotted as at D in a track D^1 similar to the track C^5 and associated with that slot. D^2 is a carriage slideable upon the track D^1 . D^3 is a pin extending through the slot D having a head D^4 adapted to travel in a slot D^5 and having at its upper end an eccentric cam D^6 controlled by a handle D^{20} whereby the carriage D^2 may be locked in position after it has been adjustably moved along the member C^7 . D^7 , D^8 are brackets projecting upwardly respectively from the member C^7 and carriage D^2 and adapted to engage the opposed edge of the binding portion of the loose leaf binder and cut away as at D^9 to support the cover as it is opened back. D^{10} , D^{10} are pins projecting outwardly respectively from the member D^7 and the member D^8 adapted to engage the ends of the pins of the loose leaf binder so as to provide a track upon which the cover portion and the loose leaves themselves may be moved back. In view of the fact that there are many different sizes of binders the adjustment of the member D^8 longitudinally is provided so that the pins may be drawn into engagement with binders of different widths.

In a further modified form of my device F is the base plate. It is comparatively narrow. It has at one end brackets F^1 , F^1 to engage one side of the loose leaf binder. It is centrally channeled at F^2 and is slotted at F^3 , the slot being at the center of the channel. F^4 , F^4 are raised supports along opposed sides of the plate for the pages B^9 and the parts B^1 , B^2 . F^5 is a carriage adapted to travel upon a shoe F^6 engaging the channel F^2 . F^7 is a holding bolt passing through the slot F^3 provided with a locking cam F^8 controlled by the handle F^9 on its upper side whereby the carriage may be released or locked at the will of the operator.

G is a strip of metal or other suitable material extending across the front of the carriage F^5 held in position thereon by means

of pins G^1 which penetrate the bracket members G^2 . Binding posts G^3 made up of separate screw threaded members G^4 , G^5 , G^6 extend forward from the strip G . These members may be screw-threaded in any one of the holes G^7 , G^8 , G^9 on the strip so that they may be moved or adjusted or pre-arranged to engage and coöperate with binders of different sizes, the member G^{10} on post member G^6 being always arranged so as to engage the end of the binding post of the book itself to bring the parts into operative relation.

The use and operation of my invention are as follows:—

The loose leaf binder is placed in the rack with the permanent or fixed side of the binder engaging the fixed stop. The posts projecting forwardly from the adjustable side of the rack are brought into engagement with the posts in the binder, that is to say, the reduced portions of the rack posts engage the perforations in the ends of the posts on the binder. The operator then releases the movable side or cover of the binder and withdraws it sliding it along the posts toward the adjustable side of the rack. This gives sufficient space between the two covers of the binder to permit the operator to move the contents back and forth along the posts. This is done while filing takes place, it being quite easy to spread the contents away from the side of the sheet so that it may slip over the posts in the usual manner. Since all the post sections are of the same size and since particularly the posts in the binder are of the same size as the posts on the rack and since they all fit, the post surface will be continuous and there will be no danger of any breaking or tearing of the sheet portions.

It will be noted that the adjustable cover of the binder has a friction grip on the post and that it may be moved along the post toward the fixed side of the cover so as to compress the contents in the usual manner. If it is desired to change the thickness of the book, different lengths of post may be used, but the post will always come substantially flush with the outside of the adjustable cover and this is possible because the rack itself provides the length of post necessary for filing.

I claim:

1. A filing rack for loose leaf binders comprising a support, stop members mounted thereon, means for adjusting the distance between said stop members, posts on one of them adapted to engage and to be in register with the binding posts, and means for clamping one stop against the other to lock the binder between them.

2. The combination with a binder having binding posts terminating in a plane substantially parallel with the binder cover of

a filing rack therefor comprising stop members, posts on one of the members adapted to engage and be in register with the binding posts and means for locking said members 5 together with the binder between them.

3. The combination with a binder having binding posts terminating in a plane substantially parallel with the binder cover of a filing rack therefor comprising stop members, posts on one of the members adapted to engage and be in register with the binding posts, means for locking said members together with the binder between them and means for releasably locking the binder 10 cover on the posts, said cover being adapted to move along the binding posts and the stop supported posts when released.

4. The combination with a binder having binding posts terminating in a plane substantially parallel with the binder cover of a filing rack therefor comprising stop members, posts on one of the members adapted to engage and be in register with the binding posts, means for locking said members 25 together with the binder between them and means for releasably locking the binder cover on the posts, said cover being adapted to move along the binding posts and the stop supported posts when released, with means 30 on such stops for limiting the downward rotational movement of the binder covers.

5. A filing rack for loose leaf binders comprising a table, a stop fixed thereon, a carriage and a second stop supported thereby movable therealong with means for locking it in position and means on the carriage for engaging and registering with the binder 35

posts of the binder and to hold it in position.

6. A filing rack for loose leaf binders comprising a table, a stop fixed thereon, a carriage movable therealong with means for locking it in position, a second stop supported by the carriage, and means on the carriage for engaging and registering with 40 the binder posts of the binder to hold it in position, said clamping means being adapted 45 for free movement of one side of the binder from the posts thereonto.

7. A filing rack for loose leaf binders and the like comprising a base plate, a stop 50 thereon adapted to engage one side of the binder, a carriage movable toward and from the stop, means for locking it in position, binding posts mounted on the carriage 55 adapted to be adjusted toward and from one another to engage the posts of varying sizes of loose leaf binders, means for locking them in position, and means for holding the binder covers in position with the binding 60 members separated.

8. In a filing rack, a base and a stop mounted thereon, a carriage mounted on said base movable to and from said stop, and binding posts mounted on said carriage, said 65 posts adapted for lateral adjustment.

In testimony whereof, I affix my signature in the presence of two witnesses this 20th day of August, 1917.
